UNITED STATES PATENT OFFICE

155,508

DESIGN FOR A SPRAYING DEVICE

Douglas D. Heimburger, Beverly Hills, Calif.

Application April 19, 1948, Serial No. 145,814

Term of patent 14 years

(CL. D62—2)

To all whom it may concern:

Be it known that I, Douglas D. Heimburger, a citizen of the United States and a resident of Beverly Hills, in the county of Los Angeles and State of California, have invented a new, original, and ornamental Design for a Spraying Device, of which the following is a specification, reference being had to the accompanying drawings, forming a part thereof.

Figure 1 is a side elevational view of a spraying device embodying my new design;

Figure 2 is a plan view of the spraying device showing my new design;

Figure 3 is a front elevational view of the same;

Figure 4 is an end elevational view of the spraying device; and

Figure 5 is a bottom plan view thereof.

I claim:

The ornamental design for a spraying device, substantially as shown.

DOUGLAS D. HEIMBURGER.
